UNITED STATES PATENT OFFICE.

MORRIS VICTORSOHN, OF BROOKLYN, NEW YORK.

HAND LEVER FOR MOTOR RESETTERS.

Application filed September 19, 1922. Serial No. 589,047.

To all whom it may concern:

Be it known that I, MORRIS VICTORSOHN, a citizen of the United States, residing at Brooklyn, in the county of Kings and State 5 of New York, have invented certain new and useful Improvements in Hand Levers for Motor Resetters, of which the following is a full, clear, and exact specification.

This invention relates to motor resetters 10 for rewinding or resetting mechanical motors of the type disclosed in my pending application filed April 17, 1922, Ser. No. 554,278.

The object of this invention is to provide 15 an improved handle for the resetting lever, said handle being adapted to fold down upon the top of the casing of the motor when not in use. The invention also contemplates means for automatically folding 20 down said handle when the latter is released, but which permits said handle to be raised to operative position when grasped by the operator. Other objects will appear as the description proceeds.

25 The invention will be first hereinafter described in connection with the accompanying drawings, which constitute part of this specification, and then more specifically defined in the claims at the end of the description.

30 In the accompanying drawings, wherein similar reference characters are used to designate corresponding parts throughout the several views:—

35 Figure 1 is a broken side elevation of a motor and resetting device constructed in accordance with this invention, showing my improved handle for the resetting lever in operative position as when grasped in the 40 hand of the operator and moved from right to left for resetting the motor.

Figure 2 is a detailed side view of the handle folded or collapsed, and

45 Figure 3 is a plan view of the handle as shown in Figure 2.

In Figure 1 the mechanism of the motor and resetter are shown mounted in a casing 1 having a slot 2 in its top and a shaft 3 journaled therein. Inasmuch as the details 50 of the motor and resetter are fully disclosed in my pending application hereinbefore mentioned, they will be described here only in general. The motor consists of a rotary member actuated by a weight which falls by 55 gravity and turns said rotary member, the

motion of which may be transmitted to mechanism to be driven through a train of gears. The rotary member is here shown as mounted on the shaft 3 and including a gear 4 and a ratchet disk having teeth 6 and rotatable with said gear 4. One of the train 60 of gears for transmitting motion to mechanism to be driven is indicated at 5. The weight 11 is mounted on an arm 8 adapted to rotate about the axis of the gear 4 said 65 arm being pivoted at 9 to a plate 10 having such rotary movement. The inner end of said arm has a tooth 7 adapted to engage any one of the teeth 6 on the ratchet disk of the motor when said arm is swung downward by the weight, as shown in Figure 1.

A segmental gear 14 is also adapted to rotate with the motor gear 4 and has a radially extending arm 13 extending below the weight arm 8 and connected thereto by 75 a link 12, so that rotation of the segmental gear 14 from right to left or anti-clockwise will raise said weight arm through the instrumentality of said arm 13 and link 12, the latter being pivotally attached to said 80 arms 8 and 13. To actuate said gear segment 14 a hand lever 16 is provided, the same carrying a spring-pressed pawl 15 to engage said segmental gear.

The upper end portion 17 of said hand 85 lever carries a handle 18 pivoted thereto at 19 just below the top of the casing 1. When raised, as shown in Figure 1, said handle 18 extends through the slot 2 in the top of the casing where it may be grasped for resetting the motor. When not in use, however, said handle may be folded down to the dotted line position in Figure 1 where it lies below the level of the top of the casing and may be covered by the hinged lid 20. The 90 handle 18 is rule-jointed to the upper end portion 17 of the resetting lever, as clearly shown in Figures 2 and 3, said handle having a lug 23 adapted to engage or abut against a lug 22 on the lever when said handle is raised or extended into line with said lever. A spring 21 is attached to the lever and adapted to bear against the handle when raised for automatically folding or collapsing the latter when released. Of 105 course, when the handle is grasped by the operator for resetting the motor the spring 21 is placed under tension sufficient to throw said handle over as soon as it is released.

I claim:

1. The combination with a motor of the character described, of a resetting lever adapted to have a reciprocating movement, and a handle pivoted to the free end of said lever and adapted to fold over thereon in the plane of movement of said lever for the purpose specified.
2. The combination with a motor of the character described, of a resetting lever adapted to have a reciprocating movement, a handle pivoted to the free end of said lever and adapted to fold over thereon in the plane of movement of said lever for the purpose specified, and means for automatically folding said handle when released from the grasp of the operator.
3. The combination with a motor of the character described, of a resetting lever adapted to have a reciprocating movement, a handle pivoted to the free end of said lever

and adapted to fold over thereon, in the plane of movement of said lever for the purpose specified, and a spring secured to the lever and adapted to bear against said handle when the latter is extended, whereby the handle is automatically folded when released from the grasp of the operator.

4. The combination with a motor of the character described, of a casing therefor having a slot therein, a resetting lever adapted to have a reciprocating movement along said slot, and a handle pivoted to the free end of said lever and adapted to project through said slot in the casing, said handle being also adapted to fold in the plane of movement of said lever to a position within the casing when not in use.

In testimony whereof I have signed this specification.

MORRIS VICTORSOHN.
